WEB TREATING APPARATUS

Hobart W. Bruker, Bordentown, N. J., assignor
to George W. Swift, Jr. Inc., Bordentown, N. J.,
a corporation of New Jersey

Application June 18, 1938, Serial No. 214,584

7 Claims. (Cl. 91—18)

Prior to the operation of corrugating a paper web by passing the same between corrugating rolls, it has been found advantageous to subject the web to the action of steam which moistens the web and also preheats it to a certain extent. The present invention relates especially to a web treating apparatus which is constructed and arranged to serve the above purposes, but in its broader aspects it should be understood that the invention may also extend to other web treating operations, in so far as the conditions of operation, requirements and results are analogous, and within the scope permitted by the prior art.

Heretofore in steaming paper webs it has been customary to draw the web over stationary shoes or similar guiding surfaces having steam containing pockets or compartments therein, and in accordance with the present invention in its broader aspects, I provide a web treating apparatus for the above purposes wherein the guiding surfaces with which the paper web contacts during the steaming operation travel at substantially the same speed as the web, thereby minimizing injury to the web which is likely to occur in the use of prior apparatus, particularly under the exceedingly high speed operation frequently demanded, and during the operation of threading a new paper web into the corrugating machine. In its more specific aspects the invention also includes certain features of construction which are advantageous in apparatus of the above character. Further objects and advantages of the invention will be in part obvious and in part specifically referred to in the description hereinafter contained which, taken in conjunction with the accompanying drawing, discloses certain specific constructions of web treating apparatus operable in accordance with the invention; the disclosure however should be regarded as merely illustrative of the principles of the invention in its broader aspects. In the drawing—

Fig. 1 is a cross sectional view showing one form of apparatus constructed to operate in accordance with the invention.

Fig. 2 is a side elevation with certain parts in section, showing the main operating parts of the apparatus shown in Fig. 1.

Fig. 3 is a diagrammatic view illustrative of one way in which apparatus as shown in Figs. 1 and 2 may be used in conjunction with corrugating rolls.

Figs. 4 and 5 are views respectively similar to Figs. 1 and 2 but showing the web treating apparatus somewhat modified in construction.

In accordance with the present invention ro-

tary members having peripheries with which the traveling paper web is engageable, and which may have a surface speed equal to that of the web, are so combined with stationary wall members as to form compartments receiving steam or the like which are closed against the escape of the steam to any substantial extent into the surrounding air, the compartments being open between the peripheries of the rotary members in such manner that the portion of the web in contact therewith substantially seals the compartments and exposes the web to the action of the steam.

In the embodiment of the invention shown more particularly in Figs. 1 and 2, the rotary members 1 which in part partition off or define the compartments above referred to, take the form of rotatable rings which are coaxially mounted and appropriately spaced apart so as to afford room between them for a series of steam receiving compartments 2, the rings 1 having circular peripheral portions 3 which are engageable with the traveling paper web 4. The peripheral portions 3 of rings 1 afford adequate support for the paper web being treated, and in this form of invention the rings 1 are not positively driven, but are caused to rotate by frictional contact with the web, at substantially the same surface speed. As shown in Figs. 1 and 2 the rings 1 are rotatably supported by stationary anti-friction bearing members 5 which latter are carried by a stationary supporting member 6 extending centrally through the members 1, the bearing members 5 and the supporting member 6 also serving in part to define the walls of compartments 3.

There are also interposed between the ring-like partition members 1 above mentioned, opposed stationary wall members 7 and 8 which cooperate in defining the compartments 3 and confine the compartments to the peripheral portions of members 1 which are engaged by web 4. In the present instance the wall members 7 and 8 are constituted by the opposite end portions of a strip 9 of spring metal (Fig. 1) which may be sprung around central support 6 and suitably affixed thereto, as by bolts 10.

The central support 6 may also be made hollow as shown in Figs. 1 and 2, to act as a steam supply conduit for compartments 2, steam being obtained from a suitable supply pipe 11. From the interior of supporting member 6 the steam may be fed to the several compartments 2 through suitable cocks or valves 12. The supply of steam to individual compartments may thus be shut off when a paper web so narrow in width is being

operated on that only a part of the compartments 2 need be in operation.

In operation of the above described embodiment of the invention the peripheral portions 3 of members 1 afford well distributed support for the web 4 as it travels past the compartments 2. The web substantially seals the open outer ends of the compartments, and at the same time its inner surface is sufficiently exposed to the action 10 of the steam. Since the surface speed of the members 1 will be substantially equal to that of the web, undue frictional effects or strains upon the web under treatment are avoided.

Fig. 3 shows diagrammatically a corrugating 15 machine construction wherein a web treating apparatus as above described is supported by uprights 13 extending up from the side frames 14 of the machine, the paper web being fed over a guide roll 15 carried by an arm 16 into arcuate 20 contact with the rotary members 1 so as to pass over the compartments 2 of the web treating apparatus which appears at the left of Fig. 3, thus causing the underside of the web to be treated as above described. The web 4 may then be lead 25 past a second web treating apparatus of similar construction, which is located above the web as indicated in the central portion of Fig. 3, so as to treat the opposite face of web 4, after which the web passes to the corrugating rolls 17 and 18 30 indicated diagrammatically at the right of Fig. 3. Preferably the compartments 2 of one apparatus are staggered crosswise of the machine with respect to those of the other apparatus, to promote 35 uniformity of treatment.

In Figs. 4 and 5 I have shown a web treating apparatus somewhat modified in construction, wherein the rotary members 19 having peripheries 20 with which the web engages as above described, are in the form of disk-like members 40 fixed to a central supporting member 21 which is rotatably mounted in suitable bearings 22 and which may be positively rotated as by gear 23 shown at the left of Fig. 5, at such rate that the surface speed of the peripheries 20 is substantially 45 equal to the rate of travel of web 4. In this form of the invention the compartments 24 (which are similar in mode of operation to the compartments 2 previously described) are defined by the members 19 above described in conjunction with opposed stationary wall members 25 and 26, these wall members being carried by a stationary supporting member 27 surrounding the central supporting member 21 above described. As shown in Fig. 4 steam may be fed 50 from a supply conduit 28 through individual valves 29 and pipes 30 to the various compartments 24. The supports 27 may be braced against angular movement by arms 31, the outer ends of which are bolted at 32 to the supply conduit 28.

In this form of the invention the rotary members 20 if positively driven will assist in the forward feed of the paper web, the mode of operation being otherwise generally similar to that above described in connection with Figs. 1 and 2.

While the invention has been disclosed as carried out by apparatus of certain specific construction, it should be understood that many changes may be made therein without departing from the invention in its broader aspects, within the scope of the appended claims.

I claim:

1. A web treating apparatus including a plurality of partition members having web engaging peripheries of substantially circular contour, said

partition members being mounted coaxially in spaced relation and being also mounted for rotation about their common axis, and stationary wall members interposed between said partition members, said rotary partition members and stationary wall members being constructed and arranged to define a compartment adapted to receive steam or the like, which compartment extends part way around the peripheries of said rotatable partition members and opens outwardly between the web engaging peripheral portions of said partition members. 5

2. A web treating apparatus including in combination spaced rotary members having peripheral portions constructed and arranged to move 15 at substantially the same speed as an advancing web contacting therewith, said rotary members defining in part a compartment for steam or the like which is interposed between said members, and stationary wall members interposed between 20 said rotary members, said stationary members also in part defining the aforesaid compartment, and said compartment opening into the space between the aforesaid peripheral portions of the 25 rotary members.

3. A web treating apparatus including a series of rotary partition members having web engaging peripheries of substantial circular contour, said partition members being mounted coaxially in spaced relation, a series of axially extending stationary wall members interposed between adjacent rotary partition members, said rotary partition members and stationary wall members being constructed and arranged to define compartments adapted to receive steam or the like 35 between adjacent rotary partition members, which compartments extend part way around the peripheries of said rotatable partition members and open outwardly between the web engaging peripheral portions of said rotary partition members. 40

4. A web treating apparatus including a series of rotary partition members having web engaging peripheries of substantially circular contour, said partition members being mounted coaxially in spaced relation, a series of axially extending stationary wall members interposed between adjacent rotary partition members, said rotary partition members and stationary wall members being constructed and arranged to define compartments adapted to receive steam or the like 45 between adjacent rotary partition members, which compartments extend part way around the peripheries of said rotatable partition members and open outwardly between the web engaging 50 peripheral portions of said rotary partition members, said apparatus including a central stationary supporting member enclosed by said rotary partition members said stationary wall members being carried by said central supporting member. 60

5. A web treating apparatus including a series of rotary partition members having web engaging peripheries of substantially circular contour, said partition members being mounted coaxially in spaced relation, a series of axially extending stationary wall members interposed between adjacent rotary partition members, said rotary partition members and stationary wall members being constructed and arranged to define compartments adapted to receive steam or the like 65 between adjacent rotary partition members, which compartments extend part way around the peripheries of said rotatable partition members and open outwardly between the web engaging 70 peripheral portions of said rotary partition members, 75

tion members, said apparatus including a central stationary supporting member enclosed by said rotary partition members, said stationary wall members being carried by said central supporting member, said central supporting member being constructed and arranged to supply steam or the like to said compartments.

6. A web treating apparatus including a series of rotary partition members having web engaging peripheries of substantially circular contour, said partition members being mounted coaxially in spaced relation, a series of axially extending stationary wall members interposed between adjacent rotary partition members, said rotary partition members and stationary wall members being constructed and arranged to define compartments adapted to receive steam or the like between adjacent rotary partition members, which compartments extend part way

around the peripheries of said rotatable partition members and open outwardly between the web engaging peripheral portions of said rotary partition members, said apparatus including a central rotary supporting member carrying said rotary partition members, and stationary supports for said wall members which extend between said rotary partition members.

7. A web steaming apparatus including a plurality of rotatable circular members having web engaging peripheries, said members being mounted in spaced relation, and stationary wall members interposed between said circular members, said wall members constituting walls of arcuate compartments interposed between adjacent circular members and opening into the peripheral space between said circular members, and means for supplying steam to said compartments.

HOBART W. BRUKER. 20
